UNITARY SYSTEM FOR TRANSMITTING
COLOR AND BLACK-WHITE PICTURES

William G. H. Finch, Spuyten Duyvil, N. Y.

Application May 3, 1937, Serial No. 140,293

5 Claims. (Cl. 178—5.2)

This invention relates to electrical transmission of pictures and more particularly relates to novel methods of and apparatus for selectively transmitting color and black-white pictures to remote points. This application is a continuation-in-part of my co-pending application Serial No. 139,365, filed April 28, 1937, entitled "Color picture transmission system."

Telepicture systems are now widely used by newspaper and other organizations in the commercial transmission of records and news photos. Such systems, however, have heretofore been limited to black-white picture transmission. Transmission of color pictures required special apparatus and operating technique, hampering its commercial development. It was necessary to prepare a plurality of color separation prints for the transmission. A color picture transmission method employing separation prints is, for example, disclosed in my co-pending application Serial No. 138,683, filed April 24, 1937.

In accordance with my present invention, I provide novel methods of and apparatus for directly transmitting a color picture or a black-white picture without requiring intermediate photography steps. The apparatus of my present invention is employed to directly scan either the color or black-white picture and generate the necessary electrical picture signals for translation at the receiving station. The apparatus is designed to selectively operate for color or black-white picture transmission and reception and thereby avoid duplication of equipment in commercial picture transmission.

My invention is particularly applicable to newspaper organizations having remotely scattered offices or plants and requiring rapid and accurate transmission of pictures either of the black-white or color variety. The transmission of color pictures and drawings such as colored comic sections, colored advertisements, and colored copy for newspapers or magazines is readily accomplished with merely the technique and precautions heretofore required for black-white picture transmission. My present invention renders the establishment of transmitting and receiving stations for color or monochrome picture transmission economical and simplifies the procedure.

Accordingly, it is an object of my present invention to provide novel methods of and means for transmitting color and monochrome pictures.

Another object of my present invention is to provide a unitary system for the selective transmission and reception of color or black-white pictures.

A further object of my present invention is to provide novel apparatus for directly and economically transmitting and receiving color or monochrome pictures.

These and other objects of my present invention will become apparent in the following description taken in connection with the drawings, in which:

Figure 1 is a plan view of a preferred embodiment of the picture transmitter of my present invention.

Figure 2 is a cross-sectional view taken along 2—2 of Figure 1 illustrating the mechanical drive for the color picture scanner at the transmitter.

Figure 3 is an elevational view of the scanner 15 adjusted for color pictures and corresponds to a view along 3—3 of Fig. 2.

Figure 4 is a cross-sectional view taken horizontally through the scanner speed-changing mechanism.

Figure 5 is a plan view of a preferred embodiment for the picture receiver adjusted to translate color pictures.

Figure 6 is a perspective view of the removable drum used with the receiver of Figure 5 for translating monochrome or black-white pictures.

Figure 7 is an illustration of the color separation prints produced at the receiver for a color picture.

Figure 8 illustrates the superposition of three 30 primary color separation prints to reconstruct a facsimile of the transmitted color picture.

A color photograph, picture, drawing, record or the like may be resolved into three individual monochrome prints corresponding to the three primary colors, red, blue and yellow. However, my invention is not limited to these colors but more or less than such primary prints may be employed. The color scene may be photographed by conventional color photography methods. A photograph of still-life may be made by taking three successive photographs of the scene using correspondingly proper light filters to produce the colored picture thereof. For action scenes, a single-exposure camera employing reflecting mirrors is used to simultaneously snap the three primary colored prints. The color filter used for each individual primary color print may be designed to pass or absorb all the color components of the light except light of the color to be printed.

Thus, for example, in producing the negative photograph corresponding to the red shades of the picture, a green filter is used; for the blue shades, an orange filter; and for the yellow shades, a violet filter.

In accordance with my present invention, the actual color picture, photograph or drawing is directly mounted in the telepicture transmitter for generating the primary color picture signals necessary to compose the color facsimile. My invention is particularly applicable to the transmission of colored paintings, drawings and the like since the use of color photograph apparatus to produce a color reproduction thereof at the transmitter is rendered unnecessary. Thus, newspapers can directly transmit colored comic sections, colored advertisements, paintings, etc. by directly inserting the originals in the transmitter as will be evident from the description following. My co-pending application 139,365, filed April 28, 1937, discloses a similar transmitter unit for producing picture signals corresponding to direct scanning of a color picture. My present invention is directed to a universal telepicture system whereby the direct transmission of ordinary black-white pictures or color pictures is accomplished.

The color or black-white picture 10 is mounted upon the drum 11 of the transmitter shown in Figure 1. Sheet clamps 12 grip opposite edges of the sheet 10 to hold it in position on the drum. Drum 11 is rotatably supported between the tail stock 13 and the shaft 14. Drum 11 is removable to facilitate mounting and de-mounting of the picture 10. Drum 11 is rotated at a predetermined speed by means of the electrical motor 15 mechanically coupled thereto by reduction gearing enclosed within housing 16. Motor 15 is preferably of the synchronous type connected to a constant frequency alternating current source by lead 17, such as a commercial sixty-cycle system. In the preferred embodiment, drum 11 is rotated at one hundred revolutions per minute.

The electro-optical scanning mechanism is located in the carriage 18 which is moved parallel to the axis of rotatable drum 11. Scanner carriage 18 is driven at a predetermined rate by means of the feed screw 20 mechanically coupled to the motor 15 by reduction gearing located at 21 and 23 interconnected by a speed-change-over device 22. Feed screw 20 is coupled to a worm lock located beneath extension plate 24 and operated into engagement and disengagement with the feed screw 20 by cam lever 25. Scanner carriage 18 is accurately guided in its transverse movement by tracks 26-26. The system is mounted upon a heavy cast-iron base 27 to minimize vibrational effects.

The mechanical arrangement of the transmitter apparatus is similar to that disclosed in my Patent No. 2,047,863 which issued on July 14, 1936, entitled "Telecommunication system", and in my co-pending application Serial No. 84,426, filed June 10, 1936, entitled "Telepicture scanning systems". As disclosed in these cases, the electro-optical scanner 18 comprises an intense source of light schematically shown at 28 which is focused by a lens system 29 to a beam 30 to produce a spot of light upon the record sheet 10. Light is refracted from the sheet 10 along path 31 to the lens system 32 which focuses the refracted light upon a photoelectric cell contained within the carriage 18 as schematically shown at 33. As drum 11 rotates, carriage 18 moves transversely thereto at a predetermined speed to the right, scanning the record sheet 10 along a helical path indicated by the scanning lines 34. The photoelectric cell 33 accordingly receives light varying in intensity in accordance with the elemental shading and/or coloring of the por-

tions of the picture being scanned. The anode of photoelectric cell 33 is connected to a suitable high voltage and generates electrical currents varying in accordance with the light impinging thereon as is well known in the electrical art. 5 The cell 33 is shown schematically connected by the electrical cable 35 to the amplifier unit 36. The operating voltages and potentials for the photoelectric cell 33 and source of light 28 are introduced through the cable 35 as will be evident to those skilled in the art and as described in my Patent No. 2,047,863. Electronic amplification of the signals generated at the photoelectric cell 33 may be performed within the carriage 18 to facilitate faithful reproduction of the signal 15 variation in the cell by amplifier 36. The picture signals are amplified at 36 and relayed to a remote receiving station across a transmission channel 37. The picture signals fall in the audio range and may be translated by modulating a 20 radio frequency carrier wave or by modulating an audio frequency carrier for transmission across a telephone line as described in my patent above referred to.

An important advantage of my present invention resides in providing a picture transmitter and receiver which can be selectively operated to directly transmit and receive color or monochrome pictures without requiring separate equipment. The herein described transmitter is similar to the transmitter described in my co-pending application Serial No. 139,365, referred to above, with the added provision of the speed-changeover mechanism 22 arranged to operate the scanner carriage 18 at one of two predetermined rates in a direction parallel to the axis of rotatable drum 11. In the transmission of a color picture by my present invention, I utilize the scanning principle disclosed in the co-pending application herein referred to, in which the 40 line-by-line scanning operations overlap so that each elemental portion of the color picture is scanned a plurality of times equal to the number of monochrome color separation prints required at the receiving station.

To accomplish the overlapping scanning operation for the colored picture, the scanner carriage 18 is fed at a predetermined fraction of its normal rate of feed for contiguous scanning corresponding to black-white picture transmission. 50 Thus, for example, where three color separation groups of signals are required, the scanner carriage 18 is advanced at one-third the normal rate corresponding to black-white picture scanning. Thus, for example, the carriage 18 may be advanced at a continuous rate equal to one inch per minute for black-white scanning and thereby scan the picture 10 (revolving at one hundred revolutions per minute) with one hundred contiguous scanning lines each minute, to execute a 60 homogeneous scanning operation. The carriage for this apparatus will be advanced at one-third this speed for color picture translation, namely, at one-third of an inch per minute, to scan the picture with one hundred overlapping scanning 65 operations in one minute. Details of a preferred embodiment for the speed change-over mechanism 22 is hereinafter described in connection with Figure 4.

The description immediately following concerns the scanning of a color picture to produce signals for the plurality of monochrome separation prints required at the receiver. The operation for scanning a monochrome or black-white picture in transmission will be described 75

subsequent to the color scanning operation. In accordance with the invention, a color picture at 10 is scanned with overlapping scanning lines and the scanning beam is successively passed through individual color filters to resolve the colored scanning variations into individual sets of color records. The scanning beam 30 is focused to a spot .01 inch wide in order to trace a scanning path across the picture .01 inch in width.

I prefer to employ three primary color prints to compose the color facsimile at the receiving station. The scanner carriage 18 is moved one-third of an inch per minute. Since the drum 11 is rotated at one hundred revolutions per minute, the scanning lines 34 overlap. If the carriage 18 were operated at one inch per minute, the scanning lines 34 would form a contiguous helical path without overlapping and uniformly traversing the sheet 10 as is ordinarily performed in black-white picture scanning. However, the scanning operation for the colored picture is such as to cause overlapping of the successive scanning paths formed at each revolution of the drum.

The refracted beam of light 31 is shown passing through a color filter disk 40 before being focused upon the photoelectric cell 33. As illustrated in Figure 3, the filter disk 40 contains three sections 41, 42 and 43, of individual color filters. These filters are either designed to individually pass through or transmit a primary color component of the colored light beam 31 and absorb the other components, or to individually absorb a primary color and transmit the remaining components. The former design employs red, blue and yellow filters, and produces signals corresponding to photographic "positives" of the primary color separation prints; for the latter design, green, orange and violet filters are used to produce signals corresponding to photographic "negatives" of the primary color separation prints. The light filter disk 40 may alternatively be interposed in the constant light beam 30 to carry out the principle of my invention.

When the refracted beam 31 is passed through a green filter, all the red color components of the picture 10 are absorbed thereby, and the remaining color components pass through to variably affect the cell 33. The light passing through the filter varies inversely in accordance with the degree of a particular primary color in the elemental portion of the picture being scanned. Variations in the intensity of the red light absorbed by the green colored filter cause corresponding current variations to be transmitted as picture signals. Similarly, an orange filter will absorb the blue picture shading and a violet filter will absorb the yellow picture components. The color record 10 being transmitted is accordingly automatically resolved into three monochrome color separation signal groups for translation at the receiver unit. These signal groups correspond to photographic "negatives" of the primary colors blue, red and yellow. The receiver may be designed to produce either "positives" or "negatives" from the signal as will now be evident to those skilled in the art.

The color filter disk 40 is rotated in synchronism with the rotation of drum 11 and at one-third the speed thereof. As shown in Figures 1 and 2, disk 40 is mechanically coupled to the gearing system contained within housing 16 and which drives drum 11. The preferred method for synchronously driving color filter disk 40 utilizes a

flexible shaft 44 connected between the stationary gear box 45 mounted on the base 27 and the movable gear box 46 mounted on the scanner carriage 18. Gear box 45 is connected to gearing at 16 by rods 47 and 48 coupled at right angles 5 by gearing box 49. The color filter disk 40 is connected to gear box 46 by rod 50 and gear box 51. The gear boxes 45, 46, 49 and 51 may contain bevelled gears for translating the drive ninety mechanical degrees at each junction. 10

The tortional cable or flexible shaft 44 permits continuous mechanical engagement of the disk 40 and the drum 11 even though the carriage 18 supporting the disk 40 is moved a considerable distance during the scanning operation. The gear box 45 is preferably centrally located with respect to the position of drum 11 so that the flexible shaft 44 will be moved through a minimum displacement and distortion. The color filter disk 40 is accordingly directly mechanically 20 coupled with drum 11 and rotates in phase synchronization therewith at one-third the speed thereof. This arrangement causes each of the color filters 41, 42 or 43 to move past refracted beam 31 in a manner such that for each revolution of drum 11, an individual filter obstructs or remains in the path of the beam 31. Thus while the drum 11 rotates once, one filter for example the green filter, will remain interposed across beam 31 so that only the red shading color 30 values of the picture are impinged upon photoelectric cell 33.

The scanning beam 30 being .01 of an inch wide, causes picture signals to be produced in amplifier 36 as though a red monochrome of the color picture 10 were being scanned during the particular revolution described. During the next revolution of the drum 11, the next adjacent color filter automatically intercepts the beam 31 due to the revolution of filter disk 40 in synchronization therewith and at one-third the rate of drum 11. This second color filter may, for example, be the orange filter so that the blue shading of the color picture 10 varies the light which impinges upon the photoelectric cell 33. 45 However, the scanner carriage 18 has only moved one-three hundredth of an inch during the previous revolution since the carriage is geared to this rate. Accordingly, the second scanning line being described will overlap the first line by two-thirds of the previous scanned line since the scanning lines are .01 of an inch wide due to the width of beam 30, and the advance of the scanner was only one-third this amount. Continuing, with the third revolution of drum 11, the third 55 or violet filter will be automatically moved into the path of the beam 31 and the scanning line upon picture 10 will overlap one-third of the first scanning line and two-thirds of the second scanning line as will now be evident, to transmit 60 the yellow monochrome primary color "negative" values of picture 10.

For each three revolutions of drum 11, the scanner carriage 18 moves a distance equal to the width of a scanning line, namely .01 of an 65 inch. Thus, during the fourth revolution of drum 11, the light beam 30 will not overlap the first scanning beam position but will be contiguous therewith as though the picture were being scanned in the ordinary manner for black 70 and white picture transmission. The green or first mentioned filter will be again interposed at the reflected beam 31 and the red components of the color picture 10 will be translated into picture signals. Continuing, the fifth rotation of 75

drum 11 brings the orange filter into view and the scanning operation is contiguous with the second scanning line formed during which the orange scanner was also used to form the blue picture signals. Similarly, the sixth operation is similar to the third described scanning operation and the violet filter comes into operation to translate the yellow components of the picture into electrical signals.

10 It will accordingly be evident that in my present invention successive overlapping scanning occurs for the plurality of primary colors for the color picture. Although I prefer to use three colors, two or four or more colors may instead be employed to recompose the color picture. Where three color pictures are used, the scanning is such that every third scanning line across the picture will be contiguous and, in effect, continuously scan the picture. Furthermore, each successive line between the three scanning operations overlap and are used to generate individual primary color separation prints. The overlapping scanning operation is performed by advancing the scanner carriage 18 at one-third the normal rate corresponding to the normal width of the scanning beam. The primary color separation prints are individually received and translated as will be hereinafter described in detail.

30 In order to transmit a monochrome or black-white picture having shading or tonations the same transmitter hereinabove described is employed. The monochrome picture is mounted upon drum 11 in the ordinary manner preparatory to scanning. The color disk 40 is removed from its position on the carriage 18. This may be readily accomplished by turning the thumb screw 52 fastening the disk 40 upon the shaft 53 motivated from gear box 51. The filter disk

40 is secured with a key to rotate with shaft 53 when mounted thereon. By removing the color filter disk 40, the reflected light beam 31 passes directly into the optical focusing system 32 to impinge upon the photoelectric cell 33. The lever 54 of the speed-change mechanism 45 is shifted to the second speed position designed to drive the feed screw 20 so that scanner carriage 18 will be moved at the rate of one inch per minute. This transverse speed of the scanner 18 is three times that corresponding to the rate used for scanning a color picture into three groups of signal values.

Accordingly, by merely removing the color filter disk 40 and throwing the speed changeover device 22 into the high speed position, the transmitter is converted to a monochrome picture transmitter and is operated similar to the transmitter disclosed in my Patent No. 2,047,863 referred to hereinabove. In my preferred illustration, the scanning beam 30 focused upon the monochrome picture to be transmitted has a width of .01 inch, the drum 11 rotates one hundred revolutions per minute, the scanner carriage moves at the rate of one inch per minute and the scanning operation is a continuous helix without overlapping as will now be evident. The transmitter of Figure 1 is accordingly universally adapted to transmit a monochrome or color picture by a simple changeover operation. The synchronizing signals are preferably transmitted once per revolution of the drum 11 for synchronizing the receiver system in a manner disclosed in my Patent No. 2,047,863.

The speed-changeover mechanism 22 is illustrated in Figure 4 which is a horizontal cross-

sectional view therethrough. Shaft 55 is driven directly from the gear-down mechanism 21 connected to the gearing box 16 which drives the drum 11. Shaft 55 is rotatably supported upon the housing of the speed changeover mechanism 22. Two sets of gears 56-57 and 58-59 are arranged within the housing and are selectively operated between positive clutching member 60. Gears 56 and 58 are rotatably mounted upon shaft 55. Gears 57 and 59 are fixedly mounted upon shaft 61 which shaft communicates to the bevelled gear 62-63 within housing 23 for driving the feed-screw 20 of scanner 18. Clutching mechanism 68 comprises driven clutch members 64 and 65 individually secured to the gears 56 and 58 respectively and a shiftable member 66 slidably keyed to shaft 55 by key 67.

The ratio between gears 56 and 57 is designed so that shaft 61 is driven three times as fast as compared to its speed when driven by the 20 gears 58 and 59. Only one set of gears at a time is used to connect shaft 55 for driving shaft 61, while the other set merely idles due to the disengagement from that set to the clutch member 66. Clutch 60 is engaged to the left 25 or right, namely, to the driven clutch member 64 or 65 by means of the lever 54 projecting from the housing 22. Lever 54 is twisted to slide the clutch member 66 and selectively engage the high or low speed settings of the speed-change 30 unit. When clutch 60 is engaged so that member 66 drives member 65, gears 58-59 cause shaft 61 and feed-screw 20 to rotate to drive carriage 18 at the slower rate, corresponding to the speed for color picture scanning. When 35 clutch 60 is engaged to the left so that clutch 66 and 64 engage, shaft 61 is rotated at the faster rate corresponding to the monochrome or black-white picture scanning operation.

Figure 5 is a plan view of a preferred universal telepicture receiver for selectively translating the electrical signals from the transmitter to produce monochrome facsimiles corresponding to the signal groups from the transmitter for either the black-white or color pictures. The receiver is motivated by electric motor 70 connected to a reduction gearing unit 71 through a speed-changeover unit 72. The unit 72 is similar to the speed changeover mechanism 22 hereinabove described in connection with Figures 1 and 4 and operates to change the speed ratio of the mechanism from low to high speed, in the present example, in the ratio of three-to-one. The reduction gear unit 71 may contain a start-stop clutch or other synchronizing means responsive to transmitted synchronizing signals for maintaining the rotation of the drum 72 in synchronism with the transmitter scanner. A suitable synchronizing system is disclosed in my Patent No. 2,047,863 hereinabove referred to. Another synchronizing system which dispenses with start-stop means is disclosed in my co-pending application Ser. No. 128,920, filed March 4, 1937. Details of a synchronizing system are not illustrated since my present invention is not directly concerned therewith. The drum 73 is rotatably mounted between the shaft 74 communicating with the gear box 71 and a tail stock 75.

The receiver scanner carriage 76 is moved parallel to the axis of drum 73 and is driven by feed screw 77 connected to the reduction gearing at 78 and 79. The gearing at 78 is directly connected to the drum shaft 74 in order that the scanner 76 be moved in exact correspondence 75

with the rotation of drum 73. The movement of carriage 76 is maintained in accurate alignment by means of the parallel tracks 80—80. The scanner carriage 76 may contain an electro-optical translating means such as a neon or crater lamp 81 connected to the output of the telepicture receiver 82. The light output of signal lamp 81 is focused upon a sensitive record sheet 83 by optical means 84 in a beam 85. Light beam 85 varies in accordance with the intensity of the received telepicture signals and is preferably adjusted to .01 inch in width, corresponding to the width of the transmitter scanning beam 30.

The sensitive record sheet 83 is mounted upon drum 73 by means of sheet mounting clamps 86 similar to the clamps 12 on the transmitter drum 11. The illustration in Figure 5 is for the reception of a color picture. In accordance with my present invention, the drum 73 used in receiving the color picture signals, is three times the diameter of the corresponding transmitter drum 11 when three color separation signal groups are employed. If only two or four color separation groups are used, the drum will correspondingly be two or four times the diameter of the standard or normal drum diameter. Figure 6 illustrates the drum 73^a which is used in place of the large drum 73 when black-white picture scanning is to be effected as will be hereinafter explained. The diameter of drum 73^a is equal to that of the drum 11 at the transmitter. Receiver drum 73 is removable from its mounting between shaft 74 and tail stock 75. Drum 73 or 73^a is selectively inserted in the telepicture receiver of my present invention in accordance with the type of picture being transmitted.

When the transmitter generates three color separation groups of picture signals corresponding to a color picture being scanned, the drum 73 having three times the diameter of the transmitter drum also has a scanning surface which is three times that of the transmitter drum. The sensitive record sheet 83 is of the same width as the transmitter sheet 10 but is three times as long in order to properly fit upon the large drum 73. Drum 73 is rotated at one-third the normal speed, namely 33½ revolutions per minute when a color picture is being received. The scanner carriage 76 is correspondingly moved at one-third of an inch per minute toward the right. The speed ratio between motor 70 and the drum 73 together with carriage 76 is arranged to operate the system at these values by moving the lever 87 of the speed-changeover mechanism 72 to the proper position. It will now be evident that the changeover device 72 serves to change both the speed of the drum 73 and the speed of the scanner carriage 76 in corresponding relationship. This factor insures contiguous scanning of the record sheet 83 by the scanning lines 88.

Translating light beam 85 being .01 inch in width traces scanning lines 88, schematically indicated on the sheet 83, .01 inch apart. The relative speeds of the carriage 76 and the surface speed of the drum 73 is such as to produce a contiguous scanning operation on the sheet 83 to form a continuous helical scanning of the record sheet without substantial overlapping of the scanning lines. Figure 7 illustrates a completed facsimile corresponding to a color picture transmission. The record sheet 83, when developed, contains three individual monochrome facsimiles B, R and Y corresponding to color separation values as generated through the color filter disk 40 hereinabove described.

The continuous scanning operation which produced the print of Figure 7 independently segregates the respective signals corresponding to the individual monochrome prints to produce spaced facsimiles as shown in Figure 7. Since the 5 rotation of color picture receiving drum 73 is set at one-third the speed of the transmitter drum 11, it will execute one revolution for each three revolutions of the transmitter drum. As already described, the overlapping scanning operation for 10 transmitting the color picture successively performs color separation operations through the synchronously driven color filter disk. The receiving system is arranged to synchronously separate the successive color discrimination signals 15 and produces monochrome facsimiles such as B, R and Y corresponding, for example, to the blue, red and yellow primary color prints for the color picture. The scenes on the three pictures are seen to be identical in appearance, size and shape 20 and are accurately arranged in parallel and vertical alignment. The particular advantages of such alignment during reception are described in my co-pending application Ser. No. 138,683, filed April 24, 1937.

The color picture reproduction is prepared by using a gelatin or other conventional transparent sensitive film for 83 and in creating light and dark areas on the film corresponding to the transmitted current variations produced from the 30 original color picture scanned through the successive color filters 41, 42 and 43. The receiver 82 may be adjusted to produce "negatives" or "positives" from the transmitted signals as desired. In order to form an actual color reproduction of the transmitter picture translucent "positives" of the B, R and Y prints are directly or subsequently formed. After the film 83 is developed, it is bleached in the conventional manner. The B, R and Y portions of the film are severed 40 and now represent the blue-red and yellow components of the color picture. In order to compose the final color facsimile, it is necessary to dye or tone the individual prints to their proper color. The blue, red and yellow prints are identified by their location on sheet 83 or in some other predetermined manner.

The tinting or coloring of the individual prints to blue, red or yellow may be performed by dyeing the bleached films with an aniline dye or by 50 toning them with metallic salt solutions which combine with the silver retained in the print in a manner well known in the photographic art. Toning the film brings out the high lights of the final picture in a better manner than the dyeing 55 process does. The monochrome colored prints are then superimposed to form an integral final picture.

In Figure 8 I illustrate a preferred manner for preparing the final colored photograph by the 60 three color prints. The tinted or toned blue, red and yellow films, B, R and Y are accurately superimposed one above the other and upon a white backing sheet 89 with transparent adhesive material. The superposition of the films is such 65 as to match the outline of the picture with corresponding portions falling in line. The scanning lines 45 on the respective prints have been drawn in to illustrate an advantage of my present invention. The scanning region lines 88 on the Y print correspond to the lines already described in connection with Figures 5 and 7. The illustration shows the R print positioned above the Y print. The scanning lines 88^a at the overlapping region of R and Y appear more dense 70 since the borders of the scanning lines overlap. 75

Similarly, the scanning line region 88^b illustrating the superposition of the three prints B, R and Y is more dense since the outline of the scanning lines 45 overlap as will now be evident.

- 5 It will be noted that all scanning lines are substantially parallel and normally overlap on superposition. The colors viewed beneath the B portion of the picture of Figure 8 contains the original coloring of the photograph since the 10 three tinted translucent films are viewed above the white backing sheet 89 and combine to produce the original elemental coloring at each portion of the picture. The overlapping of the scanning lines at 88^b evens out or tones the final 15 image so as to effectively dissolve or cause any possible outline of the individual scanning lines which may be apparent in an individual print to disappear in the final color print.
- It is to be understood that the synchronizing 20 signals are transmitted from the receiver once every revolution of the transmitter drum. However, the receiver drum 73 rotates only once for each three revolutions of the transmitter drum. Accordingly, only each third synchronizing signal 25 will be effective in orienting the receiver drum 73. The synchronizing signals which are not effective in synchronizing the larger drum rotating at one-third the speed, will appear as solid lines 90 separating the individual B, R and Y 30 monochrome facsimile prints and not interfere with the production of the prints.

The telepicture receiver of my present invention accommodates translation of the black-white or monochrome transmission from the transmitter as well as the plurality of color separation prints by direct transmission from the transmitter. The large drum 73 is removed and the normal sized drum 73^a as illustrated in Figure 6 is inserted in position between the shaft 74 and the tail stock 75. The scanner carriage 76 is adjusted in the normal manner and the scanning or translating beam 85 varying in accordance with the picture signals is of the same diameter, namely .01 inch as heretofore described. The 40 only other adjustment required is to move the lever 87 of the speed changeover mechanism 72 to the higher speed position. The drum 73^a will then rotate at the same speed as the transmitter drum 11, namely one hundred revolutions per 45 minute. During the transmission of black-white or monochrome pictures, the transmitter scanner carriage 18 is moved at the rate of one inch per minute, the speed-changeover mechanism 22 being shifted, by lever 54, to the high speed position. The transmitter and receiver for the 50 black-white pictures will accordingly operate in synchronism and with similar speed ratios and correspond to the system described in my Patent No. 2,047,863 referred to above for black-white picture transmission. My present invention accordingly permits selective transmission of color or monochrome pictures from the transmitter to the receiver with minor adjustments for either 55 type of picture.

60 In accordance with my present invention, colored monochrome or black-white photographs, pictures, drawings, and paintings of any character may be economically transmitted to remote points with the same system. Such transmission is particularly important to newspaper and magazine chains where rapid and accurate transmission of many types of copy between remote points is paramount. Such transmission is carried out with the skill and precaution ordinarily required with black-white picture trans-

mission. Colored pictures and drawings for comic sections, special feature sections, or advertisements are economically transmitted without special precautions to avoid inherent commercial picture distortions. The colored pictures are transmitted without requiring the intermediate color separation prints such as produced by color photography processes.

By suitably choosing the color filter of the filter disk at the transmitter or by suitably biasing 10 or electrically connecting the transmitter and/or receiver circuits, the receiver can directly produce "positives" corresponding to the primary color separation prints for the color picture transmitted. In a similar manner, negatives of 15 these pictures may be produced at the receiver. It is feasible to directly engrave the primary color separation prints upon a metallic plate for use with the conventional color printing process. The receiver translating unit corresponding to Figures 4 and 5 may be at the same location as the transmitter and be used to translate the picture signals generated directly from the color photograph 20 into the primary color separation prints necessary for color photo-engraving and thus 25 avoid the requirement for intermediate color photography. Modifications of my present invention will be evident to those skilled in the art and accordingly I do not intend to be limited except as set forth in the following claims. 30

I claim:

1. The method of transmitting a colored picture which comprises scanning the colored picture at a predetermined surface speed, successively filtering out different colors of the light 35 beam for successive lines of scanning to produce light intensities varying in accordance with color components of elemental portions of the picture, generating electrical signals in accordance with the varying light intensities, transmitting the 40 electrical signals to a receiving station, producing a scanning beam of light of intensity varying in accordance with the electrical signals, and continuously scanning a sensitive record sheet with the scanning beam in a contiguous scanning 45 operation at a surface speed substantially equal to said predetermined rate to simultaneously produce a plurality of monochrome facsimiles on the record sheet corresponding to the individual transmitted color value signals. 50

2. The method of transmitting a colored picture which comprises scanning the colored picture at a predetermined surface speed by overlapping scanning operations, successively filtering out different colors of the light beam for successive 55 lines of scanning to produce light intensities varying in accordance with color components of elemental portions of the picture, generating electrical signals in accordance with the varying light intensities, transmitting the electrical signals to a receiving station, producing a scanning beam of light of intensity varying in accordance with the electrical signals, and continuously scanning a single sensitive record sheet with the scanning beam in a contiguous scanning operation at a surface speed substantially equal to said predetermined rate to simultaneously produce a plurality of monochrome facsimiles on the single record sheet corresponding to the individual transmitted color value signals. 60

3. A unitary system for transmitting color and monochrome pictures comprising mechanism for electrooptically scanning a picture with a contiguous line-by-line operation at a predetermined picture surface speed; means for changing the 70

scanning operation to an overlapping line-by-line operation for color picture scanning; means for filtering the scanning light beam differently for successive lines of scanning for producing electrical signals varying in accordance with individual color components during the overlapping scanning operations on the color picture; and means for translating said electrical signals comprising means for carrying a record sheet, a recording unit responsive to said signals, a source of motive power for motivating said sheet-carrying means with respect to said unit across said record sheet at substantially said electrooptical scanning surface speed, and means for controlling the relative speed of said sheet-carrying means and said associated recording unit for simultaneously producing an individual facsimile corresponding to individual colors for a transmitted color picture.

20 4. A system for transmitting color and monochrome pictures comprising mechanism for electrooptically scanning a picture with a contiguous line-by-line operation at a predetermined surface speed including a picture carrying device, motive means for said picture carrying device, and an electrooptical scanner carriage mechanically connected to said device for motivation at a predetermined rate across said device; means for changing the contiguous scanning operation 30 to an overlapping line-by-line operation for color picture scanning; removable means for filtering the scanning light beam differently for successive lines of scanning for successively producing electrical signals varying in accordance with individual color components during the overlapping scanning operations on the color picture; and means for translating said electrical signals comprising means for carrying a record sheet, a recording unit responsive to said signals, a source of motive power for motivating said sheet carrying means with respect to said unit across said record sheet at substantially said electrooptical

scanning surface speed, and means for reducing the speed of rotation of said sheet-carrying means and said associated recording unit for producing an individual facsimile corresponding to individual colors of a transmitted color picture.

5 5. A unitary system for transmitting color and monochrome pictures comprising mechanism for electrooptically scanning a picture with a contiguous line-by-line operation at a predetermined surface speed including a picture carrying device, motive means for said picture carrying device, and an electrooptical scanner carriage mechanically connected to said device for motivation at a predetermined rate across said drum; means for reducing said predetermined motivation rate of said carriage to cause an overlapping line-by-line operation for color picture scanning comprising a speed change-over apparatus connected between said picture carriage device and carriage at the mechanical connection therebetween; removable means for filtering the scanning light beam differently for successive lines of scanning and for producing electrical signals varying in accordance with individual color components during the overlapping scanning operations on the color picture; and means for translating said electrical signals comprising means for carrying a record sheet, a recording unit responsive to said signals, a source of motive power for motivating said sheet-carrying means and operating said unit across said record sheet at substantially said electrooptical scanning surface speed and means for changing the relative speed of said sheet carrying means and said associated recording unit for producing an individual facsimile corresponding to individual colors for a transmitted color picture consisting of a speed reduction device connected between said source of motive power and said sheet carrying means.
